[57] CLAIM

The ornamental design for a rotary peristaltic pump, as shown and described.

DESCRIPTION

FIG. 1 is a perspective view of a rotary peristaltic pump showing our new design;
FIG. 2 is a front elevation view thereof;
FIG. 3 is a top view thereof;
FIG. 4 is a right side elevation view thereof;
FIG. 5 is a rear elevation view thereof;
FIG. 6 is a left side elevation view thereof; and,
FIG. 7 is a bottom view thereof;
FIG. 8 is a perspective of a rotary peristaltic pump showing a second embodiment of my new design;
FIG. 9 is a front elevation view of FIG. 8;
FIG. 10 is a top view of a FIG. 8;
FIG. 11 is a right side elevation view of FIG. 8;
FIG. 12 is a rear elevation view of FIG. 8;
FIG. 13 is a left side elevation of FIG. 8; and,
FIG. 14 is a bottom view of FIG. 8.
